UNITED STATES PATENT OFFICE.

HARRY E. EASTERDAY, OF ALBERT, WEST VIRGINIA.

RAIL-JOINT.

No. 798,890.

Specification of Letters Patent.

Patented Sept. 5, 1905.

Application filed June 23, 1905. Serial No. 266,602.

To all whom it may concern:

Be it known that I, HARRY E. EASTERDAY, a citizen of the United States, residing at Albert, in the county of Tucker and State of West Virginia, have invented certain new and useful Improvements in Rail-Joints, of which the following is a specification.

This invention relates to means for joining the meeting ends of rails; and the invention particularly embodies a special construction of rail whereby the same may be interlocked with an adjacent rail to afford a substantial and rigid connection therewith and at the same time to allow of longitudinal expansion and contraction of the rails by heat and cold.

In carrying out the invention the ends of the rails are so formed as to afford the interlocking feature above-mentioned, and the necessity of fish-plates, bolts, or like parts is obviated.

While the essential and characteristic features of the invention are susceptible of modification, still the preferred embodiment of the invention is illustrated in the accompanying drawings, in which—

Figure 1 is a longitudinal vertical sectional view showing the rails interlocked together as in actual use in my invention. Fig. 2 is a plan view looking from beneath. Fig. 3 is a transverse vertical sectional view taken on the line III III, Fig. 1. Fig. 4 is a perspective view, taken from below, of the expansible longitudinal projections on the upper projection of the rail and one of the wedges to fit in one of said expansible longitudinal projections. Fig. 5 embodies a sectional view of a modification of the invention.

Referring to the drawings more specifically, 1 designates the rails; 2, the base thereof; 3, the web, and 4 the thread. In the present invention one end of the rail is cut away longitudinally for some distance at approximately the middle of the web 3, including the lower portion of said web and the base 2. Extending downwardly from the projection now formed at the end of the rail are one or more longitudinal projections 5, which are grooved or slotted at their lower extremities to admit of wedges 6. The opposite end of the rail 1 is cut away in a manner just the reverse of the first-mentioned cut-away portion in order that it may fit neatly and accurately onto said first-mentioned cut-away portion, as shown in Fig. 1. The projection now formed at this end of the rail contains slots or apertures 7

for the purpose of receiving the projections 5, said slots 7 being somewhat greater in length than the projections 5 to permit of longitudinal contraction or expansion of the rail. The wedges 6 are grooved at their heads for the purpose of being held in place by a rod or bar 8 of any preferred material. Said rod or bar 8 extends beneath the series of wedges 6, parallel with the rail, and rests upon or into the ties on either side of the joint.

It will be seen from the drawings and from the above specific description that in the assembling of the rails the projections 5 fit snugly at their sides into the slots 7. The wedges 6 are then driven into the grooves in said projections 5 from beneath, causing the expansion of said projections and the consequent locking of the rails. The rod or bar 8 is then placed beneath the wedges 6 for the purpose of keeping them in place.

Because of the fact that the ends of rails by the use of the present invention fit so securely, caused chiefly by the nature and construction of the expansible longitudinal projection 5, it can readily be seen that in use upon electrical roads or upon roads where electricity is the means of propulsion there is absolutely no necessity for "bonding" or copper or other kinds of wires or plates for the passage from one rail to another of the current.

The modification shown in Fig. 5 is the construction as generally used in connection with mine-car rails and rails used on other similar small traction-lines.

Having thus described the invention, the following is what I claim as new therein and desire to secure by Letters Patent:

1. In a rail-joint, the combination of adjacent rails, a projection extending from the end of one rail, formed of the thread and a portion of the web of the rail, a projection extending from the end of the other rail formed of a portion of the web and the base of the rail, male and female portions formed respectively in each of said projections, and wedges for securing said male portions within said female portions.

2. In a rail-joint, the combination of adjacent co-operating rails, a projecting member extending from and forming part of one rail, adapted to fit snugly over a projecting member extending from and forming part of the lower portion of the other rail, projections depending from the first-mentioned projecting member adapted to fit within slots within the

projecting member of the other rail wedges expanding the projections against the sides of the slots, and means for permanently holding said wedges in place.

5 3. In a rail-joint, the combination of adjacent rails, projections from the end of one of said rails adapted to fit within slots in the end of the other of said rails, wedges for securing the projections in the slots, and a rod or bar

for holding said wedges in place, substantially as described.

In testimony whereof I affix my signature in presence of two witnesses.

HARRY E. EASTERDAY.
